UNITED STATES PATENT OFFICE.

WILLIAM SCHULTZ, OF LAUREL, IOWA.

WINDOW SHADE AND CURTAIN BRACKET.

1,182,804.

Specification of Letters Patent.

Patented May 9, 1916.

Application filed February 7, 1916. Serial No. 76,731.

To all whom it may concern:

Be it known that I, WILLIAM SCHULTZ, a citizen of the United States, residing at Laurel, in the county of Marshall and State 5 of Iowa, have invented new and useful Improvements in Window Shade and Curtain Brackets, of which the following is a specification.

This invention relates to improvements in 10 window shade and curtain brackets adapted to provide supporting bearings for the roller of a window shade and to also provide supports for a curtain pole, the object of the invention being to provide an improved device 15 of this character which is extremely cheap and simple and which may be readily attached to or removed from a window casing.

The invention consists in the construction, 20 combination, and arrangement of devices, hereinafter described and claimed.

In the accompanying drawings: Figure 1 is a perspective view of a combined window shade and curtain pole bracket constructed 25 and arranged in accordance with my invention. Fig. 2 is a plan of the same.

My improved combined shade and curtain bracket is made from a single piece of sheet metal and comprises an attaching portion 1 30 which is adapted to be secured to one side of a window casing, a lug or arm 2 which is at right angles to the attaching portion and projects from the front side thereof and which is provided with a bearing opening 35 3 in which one journal of a shade roller may be mounted, and a fork 4 which extends upwardly from the outer end of said lug or arm 2 and which comprises a pair of members or arms 5, 6, adapted to receive a curtain pole between them. The member 5 is 40 formed at the upper end of a web 7 which is bent at right angles to the arm or lug 2 and the arm 6 is formed at the upper end of a web 8 which projects from the upper side

of and the major portion of which is in a 45 common plane with the said lug or arm 2. By the provision of the web 7, a reinforce 50 is provided for the outer end of the lug or arm 2 to strengthen the construction of the bracket and to strengthen the web 8. Said 55 web 8 has its upper portion offset and twisted to an angle of about 45 degrees and the arm 6 is correspondingly twisted so that the opposing faces of the said arms 5, 6, are adapted to bear against opposite sides 60 of the pole.

By the provision of the pole supporting fork arms at the upper side and outer end 65 of the bearing portion of the bracket, the construction of the device is greatly simplified, effecting a corresponding economy in its manufacture and the bracket is adapted to hold the pole at a point higher than and projected farther from the window than the 70 roller of the shade.

Having described the invention, what is 75 claimed is:

The herein described integral sheet metal window shade and curtain bracket comprising an attaching portion to bear against one 80 side of a window casing, an arm projecting outwardly from one side of the attaching portion and arranged at right angles thereto, said arm having a bearing in its upper side for a shade roller, a web at the outer end of the arm, at right angles thereto and provided at its upper side with an upwardly and outwardly bent fork arm to bear against the outer side of a curtain pole, and an inner fork arm forming an upper extension 85 of the outer portion of said bracket arm.

In testimony whereof I affix my signature in presence of two witnesses.

WILLIAM SCHULTZ.
